UNITED STATES PATENT OFFICE.

ULYSSES S. DRAYER, OF ALTOONA, PENNSYLVANIA.

DRAFT-RIGGING JOINT CONNECTION FOR CAR-COUPINGS.

SPECIFICATION forming part of Letters Patent No. 769,065, dated August 30, 1904.

Application filed November 12, 1903. Serial No. 180,841. (No model.)

To all whom it may concern:

Be it known that I, ULYSSES S. DRAYER, a citizen of the United States, residing at Altoona, in the county of Blair and State of Pennsylvania, have invented new and useful Improvements in Draft-Rigging Joint Connections for Car-Couplers, of which the following is a specification.

This invention relates to railway draft appliances, and has special reference to the means for connecting the car-coupler with the draft-rigging.

To this end the invention primarily has in view an improved type of joint connection for coupling the draw-bar of an automatic or other car-coupler with the draft-rigging.

In carrying out the invention the same has specially in view the provision of a joint connection of the ball-and-socket type, which is utilized as the means for connecting the rigid draw-bar of the car-coupler with the draft-rigging, whereby the cushioning or buffer action of the rigging is not interfered with, while at the same time the draw-bar, and hence the entire car-coupler, is permitted to freely swing to either side in a lateral direction upon a vertical axis and also to rock or oscillate axially. By reason of this movement provided for through the medium of the improved joint the car-coupler will freely accommodate itself to curves or rocking vibrations without straining or otherwise impairing the draft-rigging.

In the ordinary types of draft-rigging connections for car-couplers no provision is made to accommodate rocking or oscillating vibrations imparted to the draw-bar, and hence a wrenching or straining is frequently imposed directly upon the draft-rigging. This is obviated by the present invention, which, furthermore, provides an arrangement which enables long cars to easily round curves without imposing undue stress on the rigging.

With these and many other objects in view, which will more readily appear as the nature of the invention is better understood, the same consists in the novel construction, combination, and arrangement of parts hereinafter more fully described, illustrated, and claimed.

The essential feature of the invention in-

volved in the double type of ball-and-socket joint providing for the lateral swinging and axial rocking of the draw-bar is susceptible to structural modification without departing from the scope of the invention; but a preferred embodiment of the latter is shown in the accompanying drawings, in which—

Figure 1 is a side elevation, partly in section, of a draft-rigging and car-coupler united through the medium of the improved ball-and-socket joint connection contemplated by the present invention. Fig. 2 is an enlarged vertical sectional view of the joint or joint connection, the line of section being longitudinal of the rigid draw-bar of the car-coupler. Fig. 3 is a vertical cross-sectional view of the joint or joint connection on the line 4-4 of Fig. 2. Fig. 4 is a sectional plan view on the line A-B of Fig. 2. Figs. 5 and 6 are half-sectional views in the same plane as Figs. 2 and 3, but illustrating a construction omitting the metallic wear-cups interposed between the contact-faces of the bearing-ball segments and the socket bearing-blocks coöperating therewith.

Like references designate corresponding parts in the several figures of the drawings.

In utilizing the improved joint for connecting the draw-bar of the car-coupler with the draft-rigging of the car no special change is involved in the construction and mounting of the draft-rigging nor in the construction and operation of the coupler, which latter is preferably of the automatic type, as the invention possesses special utility in connection therewith. Hence for illustrative purposes there is shown in the drawings an ordinary automatic car-coupler designated by the numeral 1 and which embodies in its organization the usual rigid draw-bar 2, extending beneath the car-body and designed to have a coupled connection with the draft-rigging. This draft-rigging includes a buffer device (designated in its entirety by the reference-numeral 3) and embodies the usual means to provide for resisting and cushioning the longitudinal thrust of the draw-bar during the car-coupling operation. The said buffer device 3 is provided at its outer end with the usual follower-head 4, receiving the initial impact or thrust of the

draw-bar and yielding therewith in the direction of such thrust, said follower-head 4 being arranged to lie at the extreme inner end of the rigid draw-bar 2, as plainly shown in Fig. 1 of the drawings. In addition to the buffer device 3 the draft-rigging includes the draft-rigging yoke 5, embodying the upper and lower longitudinally-disposed bar members 6, provided at their outer extremities with the inturned holding flanges or lugs 7, which assist in properly securing in place the upper and lower socket bearing-blocks 8 and 9, which coöperate with the joint-head 10 at the inner end of the draw-bar to provide a double ball-and-socket-joint connection between such draw-bar and the draft-rigging. The joint-head 10 at the inner end of the draw-bar 2 is a rigid part of the latter and is preferably formed integral therewith. The said head 20 essentially consists of a ball body or enlargement which is designed to constitute the ball element of a universal or ball-and-socket joint which provides the connection between the draw-bar and the draft-rigging, and said ball body or enlargement is usually cast in a hollow formation with a plurality of interior inwardly-projecting strengthening-ribs 11, located therein and providing sufficient reinforcement for the whole body to enable it to 30 stand the strain to which the same may be subjected.

The essential parts of the ball-body constituting the joint-head 10 are the elements thereof which provide, in connection with the 35 socket bearing-blocks 8 and 9, a double ball-and-socket joint, and to this end the joint-head or ball-body is formed, at the upper and lower sides thereof, with the upper and lower bearing-ball segments 12 and 13, respectively, 40 which segments are the active ball members of the head and have a bearing fit in the upper and lower blocks 8 and 9. Said bearing-ball segments 12 and 13 are necessarily segments of the same circle, and to provide for 45 accomplishing the movement contemplated by the present invention the joint-head is also constructed at the upper and lower sides thereof with the deeply-channeled upper and lower bearing-recesses 14 and 15, respectively, 50 of greater depth than the elevation or projection of the segments 12 and 13 in order to receive therein the active portions of the socket bearing-blocks 8 and 9. The bearing-ball segments are therefore located within 55 and constitute the bases of the recesses 14 and 15, and at this point it is to be observed that in a direction longitudinal of the draw-bar the said recesses are substantially of the same width as the socket bearing-blocks fitting 60 therein; but in a transverse direction, as plainly shown in Figs. 3 and 4 of the drawings, the recesses 14 and 15 are of greater width than the transverse width of the said blocks 8 and 9, whereby a restricted axial 65 rocking or wrist-like movement is provided

for the draw-bar and the joint-head carried thereby. It will also be observed that the inner walls of the bearing-recesses 14 and 15 are preferably curved, as indicated at 16, to conform to the correspondingly curved or 70 convexed side faces or edges 17 of the socket bearing-blocks to insure an easy bearing between the joint-head and the bearing-blocks in the rocking or axial movement of the head. To complete the ball-and-socket-joint bearing, 75 the upper and lower socket bearing-blocks 8 and 9 are provided at their inner faces with the concaved ball-seats 18, with which conform the bearing-ball segments 12 and 13 of the joint-head. 80

Various expedients may be resorted to for properly connecting the parts together to maintain them in relative working positions; but a preferable construction is shown in the drawings and consists, primarily, in the employment of a plurality of joint-retaining sleeves 19, flanged or otherwise secured in the sleeve-openings 20, provided in the upper and lower socket bearing-blocks 8 and 9. While any desired number of these joint-retaining sleeves may be employed, still the preferable construction embodies a pair of these sleeves arranged in the plane of the longitudinal center of the joint connection and extending vertically from one socket bearing-block to the other, thereby providing a retaining connection for holding the ball-and-socket members of the joint in operative relation at all times. In addition to retaining sleeves for the joint members proper there are also preferably employed suitable fastenings for permanently securing the joint to the upper and lower bar members of the draft-rigging element. These fastenings preferably consist of the headed pins or bolts 21, 100 passed longitudinally through the sleeves 19 and secured in openings 22, provided in the upper and lower bar members 6 and 7 of the draft-rigging element. To accommodate the sleeves 19 and the fastenings 21 incased therein, the upper and lower ball-segments of the joint-head are provided with enlarged clearance-holes 23, which are of sufficient size to accommodate the lateral swinging and axial 105 rocking or wrist movement of the joint-head. 110

From the foregoing it is obvious that the car-coupler draw-bar 2 is free to swing upon the ball-joint laterally in both directions, and also it is capable of a rocking, oscillating, or axially-turning movement limited by the side 120 stop abutments 24, which are formed by the opposite side walls of the recesses 14 and 15. These movements of the draw-bar do not interfere with the buffer or cushioning action of the draft-rigging, as in the coupling operation the entire joint moves against the buffer device 3. 125

While the construction already described and which is shown in Figs. 5 and 6 completely embodies the essential features of the inven- 130

tion to permit of the joint movement of the draw-bar referred to, still the preferable and practical form of the joint or joint connection is shown in Figs. 2 and 3 of the drawings. 5 In these figures of the drawings is illustrated an additional element possessing special utility in preserving the life and working fit of the joint. This additional element consists of a metallic wear-cup 25, arranged in each of the 10 bearing-recesses 14 and 15 and interposed between the working faces of the ball-segments 12 and 13 and of the socket bearing-blocks 8 and 9. Each of the metallic wear-cups 25 essentially 15 comprises a concavo-convex base-section 26, which conforms to and closely registers with the convex surface of the ball-segment with which it is associated and the complementary concave seat 18 of the contiguous bearing-block, thus providing a continuous reinforced 20 wear-surface between the ball-segment and its adjacent socket-block to provide for taking up the transverse wear of the joint incident to the movement of the draw-bar. The outturned peripheral side-retaining flanges 27 of each 25 cup take over and embrace the convexed side faces or edges 17 of the socket bearing-block with which it is associated, and, as plainly shown in Fig. 3 of the drawings, the wear-cups are of the same transverse and longitudinal 30 width as the socket bearing-blocks, whereby the latter therefore maintain the wear-cups in centered relation to the axis of the joint. To further provide for the axial rocking or wrist-like movement of the coupler-shank, the faces X of the wear-cups, together 35 with the faces 16 of the coupler-body 10, are made arcs of circles concentric with each other and centered at the coupler-knuckle. Hence when pulling cars around sharp and reverse 40 curves, the couplers being together, the point of contact between the knuckles of the couplers forms the center around which the outside faces X of the wear-cups revolve. This, in 45 connection with the oblong holes 23 in the body 10, insure a wrist-like movement, such as is required to prevent the couplers from falling.

Other changes in the form, proportion, and minor details of construction may be resorted 50 to without departing from the spirit of the invention or sacrificing any of the advantages thereof.

Having thus described the invention, what is claimed, and desired to be secured by Letters 55 Patent, is—

1. In a joint of the class described, the combination of a draft-rigging yoke carrying upper and lower bearing-blocks, the coupler draw-bar provided at its inner end with a rigid 60 joint-head in the form of a ball-body having upper and lower bearing portions registering with said upper and lower bearing-blocks and retaining means coupling the ball-body to the yoke.

2. In a joint of the class described, the com-

bination of a draft-rigging yoke carrying upper and lower bearing-blocks, and the coupler draw-bar provided at its inner end with a rigid head in the form of a ball-body having upper and lower bearing members registering with 70 said upper and lower bearing-blocks and also provided with upper and lower recesses receiving the said blocks, substantially as and for the purpose described.

3. In a joint of the class described, the combination with the upper and lower members of a draft-rigging yoke, of upper and lower socket bearing-blocks fitted to the inner sides of the yoke members and provided at their inner faces with concaved ball-seats, the coupler draw-bar provided at its inner end with a rigid joint-head in the form of a ball-body provided with upper and lower bearing-ball segments registering respectively in the seats of the upper and lower socket bearing-blocks, 80 and with upper and lower bearing-recesses receiving the blocks and of greater transverse width than the same to permit axial oscillation of the joint-head.

4. In a joint of the class described, the combination with the upper and lower members of a draft-rigging yoke, of upper and lower socket bearing-blocks fitted to the inner sides of the yoke members and provided at their inner faces with concaved ball-seats, the coupler draw-bar provided at its inner end with a rigid joint-head in the form of a ball-body provided with upper and lower bearing-ball segments registering respectively in the seats of the upper and lower socket bearing-blocks, 90 and with upper and lower bearing-recesses receiving the blocks and of greater transverse width than the same to permit axial oscillation of the joint-head, a plurality of joint-retaining sleeves connecting the upper and lower socket bearing-blocks and extending through clearance-openings in the joint-head, and fastening-pins extending through the sleeves and secured to said upper and lower members of the draft-rigging yoke.

5. In a joint of the class described, the combination of the car-draft rigging carrying oppositely-arranged socket members, the coupler draw-bar carrying a rigid ball member held between and common to both of the socket members, and metallic wear-cups interposed between the working faces of the said ball-and-socket members.

6. In a joint of the class described, the combination of a car-draft rigging carrying oppositely-arranged socket bearing-blocks the coupler draw-bar provided with a rigid joint-head and having upper and lower bearing-ball segments and bearing-recesses about said segments, and flanged wear-cups embracing 120 the socket bearing-blocks and having concavo-convex bases registering with the ball-segments and the complementary faces of the 125 socket bearing-blocks.

7. In a joint of the class described, the com-

bination of the car-draft rigging carrying oppositely-arranged socket bearing-blocks, the coupler draw-bar provided with a rigid joint-head having upper and lower bearing-ball 5 segments, flanged wear-cups carried by said blocks and having concavo-convex bases registering with the ball-segments and having the front and rear faces made concentric arcs,

whose center is located upon the coupler-knuckle.

In testimony whereof I affix my signature in presence of two witnesses.

ULYSSES S. DRAYER.
